FOREIGN PATENT DOCUMENTS

JP 3-21304 1/1991

Primary Examiner—Robert M. Spear*Assistant Examiner*—Susan Bennett Hattan(74) *Attorney, Agent, or Firm*—Ohlandt, Greeley, Ruggiero & Perle LLP(57) **CLAIM**

It is claimed the ornamental design for a cap for a tubular dispenser, as shown and described.

DESCRIPTION

FIG. 1 is a front view of a cap for a tubular dispenser according to the present invention;

FIG. 2 is a side view thereof;

FIG. 3 is a top view thereof; and,

FIG. 4 is a rear view thereof.

The broken line in FIG. 3 represents the bounds of the claimed design; all other broken lines are for illustrative purposes only. All broken lines form no part of the claimed design.
